UNITED STATES PATENT OFFICE.

EDWARD E. CLEMENT, OF WASHINGTON, DISTRICT OF COLUMBIA.

ELECTRICAL SWITCHING APPARATUS FOR TELEPHONE SYSTEMS.

1,029,591.

Specification of Letters Patent. Patented June 18, 1912.

Application filed January 6, 1906. Serial No. 294,977. Renewed December 31, 1910. Serial No. 600,277.

To all whom it may concern:

Be it known that I, EDWARD E. CLEMENT, a citizen of the United States, residing at Washington, in the District of Columbia, 5 have invented certain new and useful Improvements in Electrical Switching Apparatus for Telephone Systems, of which the following is a specification, reference being had therein to the accompanying drawings.

10 My invention relates to electrical switching apparatus for telephone systems and has for its object the improvement of such apparatus in both construction and arrangement, as will appear from the following description.

15 My invention relates particularly to apparatus of that class commonly known as "automatic", wherein switching devices are mechanically actuated to interconnect circuits, their operation being ordinarily controlled electrically from a distance.

20 In some cases, and in some systems which I have designated as "semi-automatic", those machine or automatic switching devices are 25 combined with manual apparatus. In other cases or systems the general equipment is all manual, with auxiliary devices of an automatic nature.

25 My present invention is applicable to any 30 system in which automatic or machine switching devices are to be employed, whether full automatic, semi-automatic, or manual with automatic branches or auxiliaries.

35 The gist of the invention lies in the design of what I may call the switch unit, that is to say, the individual mechanism which forms the unit whose multiplication makes up a system or exchange, and the use in connection with this switch unit of what I shall hereinafter call unit sections, each made up 40 of a frame work or casing adapted to receive and hold a certain number of the switch units constituting a group, each group being 45 in itself a self-contained and complete subdivided section of an exchange equipment.

50 Perhaps the most important feature of my design and of the invention is the capability of apparatus thus made to be built up by aggregating unit switches in a section, and then by aggregating sections, each complete in itself, to form a complete exchange or switching outfit of any desired size and capacity. So far as I know this has never 55 before been accomplished. Heretofore, a considerable part of telephone engineering

work has consisted in the design of exchange equipments, that is to say in the preparation of plans and specifications for the building and installation of complete switchboards or automatic outfits, with the auxiliary apparatus and fittings appertaining thereto. It has been necessary to design and install each plant as a whole, its so-called "ultimate capacity" being limited, with the "present 60 equipment" anything desired within the limit. The principal reason for this in manual switchboard installations has been that in nearly all cases they have employed multiple switchboards, but in all installations an additional reason has been found in the disregard of all sub-division in the general arrangement, cable and wiring plan.

65 According to my present invention I provide switch units which are uniform, and each of which is interchangeable with every other unit. This permits great economy in manufacture. I mount the parts of each unit on a perfectly flat skeleton frame, and provide a unit section or cabinet into which the frames can be slid edgewise. Upon the back of each unit section or cabinet I mount contact strips of the switches, these being 70 straight strips containing preferably one hundred sets of springs, with platinum 75 points for all contacts included in talking circuits. The switch frames slide into the cabinets from the front, and are provided with guides so that they will automatically 80 align themselves with the contact strips 85 when in place. I make the frames of the switches, the unit sections or cabinets, and the contact strips all of metal, so that except for the necessary insulation on the 90 switch magnets, and between the contact 95 springs on the strips, there is absolutely nothing combustible in any part of the outfit. All wire connections are made to the contact strips on the back and outside thereof, the same being inclosed by metal covers 100 fitted on the backs of the cabinets, the fronts of which are also fitted with covers which may be either all of metal or metal frames with glass panels.

105 The unit sections or cabinets being all the same, another great economy in manufacture is brought about, and instead of having to design complete frame-works and enclosures for switching outfit, it is merely necessary to pile up unit section cabinets in any desired manner to form the required aggregation of switches for any given ex-

change. This arrangement is exceedingly flexible, and as the design of the back covers of the cabinets leaves the same open at top and bottom, the wiring and cables can be led up and down without any special provision being made therefor, no matter what the combination. Thus, sections may be piled up to form banks of any desired height and of any length, or they may be piled to form bays or aisles, or irregularly around the sides of a room, or in any other desired manner. The usual provision will of course have to be made in every case for cables, which may be the employment of a false floor upon which the switch units are placed.

In order to render any aggregation of units complete, I provide top and base sections which are standard units in themselves, adapted to register with any unit sections or cabinets, and with the covers thereof back and front.

It will be perceived from this brief statement that I have produced what may be called a system of mechanical construction and arrangement of automatic switches which is very flexible, highly efficient, and adapted to produce the greatest economy in manufacture.

In conjunction with my switches as such I employ relays, for controlling and directing the various switching operations, and these relays, which in themselves form no part of the present invention, are separately mounted on racks or frames, and inclosed in dust and moisture-proof cases. Suitable provision being made for the inclosure and protection of the wire and cables in the plant, it is therefore possible in the practice of my invention to have every part thereof practically fire-proof and non-combustible, an exceedingly important point, not only because of the reductions it effects in insurance rates, but because it obviates all danger of interruption in exchange service due to fires originating in the exchange apparatus. If there should happen to be a burn-out due to some high potential discharge or alien current getting past the protective devices of an exchange, the damage done in my system would be limited strictly to the particular unit section in which the burn-out takes place.

I believe I am the first to design a system or outfit of apparatus which can be assembled and operated in the manner stated, and I therefore desire my claims to be given a broad construction.

My invention is illustrated in the accompanying drawings, in which—

Figure 1 is a side view of a switch unit and its contact bank. Fig. 2 is an edge view of the same, part of the switch frame being broken away to show the magnet mountings. Fig. 3 is a detail figure presenting a side

view of the magnet mountings, armature, and working pawls. Fig. 4 is a face view of the left-hand vertical member in Fig. 3. Fig. 5 is an end view of the contact bank and the switch spindle with the operating studs thereon. Fig. 6 is a detail figure showing a portion of the switch spindle, together with the fixed detent which holds the same against rotation during its vertical movement. Fig. 7 is a side view similar to Fig. 1, showing the manner of mounting the switch and its bank in the unit section frame or cabinet. Fig. 8 is a face view of a unit section, with five switch units mounted therein. Fig. 9 is an end view of the same. Fig. 10 is a rear view of a portion of the same. Fig. 11 is a top plan view of the same. Fig. 12 is a front view of a cabinet formed by aggregating four unit sections with bases and tops. Fig. 13 is an end view of the same. Fig. 14 is a detail perspective view of a pair of fastening devices for securing the unit sections together.

Fig. 1 shows a unit switch, with its contact bank, removed from the frame or cabinet. This switch is marked Z, and the contact bank, which is manufactured and completely assembled apart from the switch, is marked Z'. The switch comprises a flat open frame, z^{21} , having projecting ends, z^{22} , z^{23} , and a central lateral displaced portion, z^{24} , forming one side and the ends of a rectangle in which I locate the operating magnets, K, L, W. The corners of the rectangle are preferably connected with the corners of the frame by the webs, z^{25} , which merge into a flange, z^{26} , which extends entirely around the frame and serve a double purpose; it not only stiffens and strengthens the structure, but the end flanges slide in grooves in the unit section cabinet and thereby support the switch.

Extending longitudinally of the frame, and parallel to the long members thereof, is the tubular operating spindle, z , sliding upon end studs z^{17} , z^{18} , which are rigidly secured to the end pieces z^{22} , z^{23} , respectively. The spindle, z , is broken in the middle to receive the ratchet member, which has a vertical ratchet, z^{27} , with eleven annular teeth, and a rotary ratchet, z^{28} , with straight teeth around its periphery. These ratchets are cut in a solid piece of brass or other suitable metal, which has projecting end studs, z^{29} , z^{30} , brazed into the divided ends of the tube, z . The studs or posts, z^{17} , z^{18} , are shown of considerable length, and in fact I find it advisable to make them as long as possible, allowing for the length of the ratchet body, and the necessary movement of the tube or spindle. The end studs are of course spaced so as to permit free up and down as well as rotary movement of the spindle, and their length, by giving an extended bearing within the tube, prevents

130

binding or friction, and also adds to the stiffness and insures good alinement. By making one of the end studs of sufficient length and diameter as respects the spindle 5 to give the requisite rigidity and provide the proper bearing surfaces for the spindle, only one such end stud may be used.

Inside the rectangle formed by the frame member, z^{24} , are secured three soft iron 10 frames, W' , l and k . The first of these forms a part of the magnetic circuit of the release magnet W , and serves also to support the release bar, w , having the pawls or fingers, w^4 , w^5 . In addition I fasten to this 15 member, W' , a knife edge detent bar, w^6 , best shown in Figs. 4 and 6, and concealed by the member, w , in Fig. 1. This knife edge is engaged by some one of the teeth of the rotary ratchet, z^{28} , after it has been 20 turned and the spindle is being raised, and the adjustment of the parts is such that the spindle cannot be turned after it has stepped up vertically to the first contact position. Because of lack of space, Fig. 1 is slightly 25 shortened, and is shown with the first vertical step of the spindle at once bringing a stud into engagement with the first contact in its series; but attention is called to the fact that in describing the circuit arrangement, I have stated that this may and in the 30 circuit shown should require two steps, hence the arrangement in Fig. 1 may be changed without altering the mechanism. the primary or initial position of the studs 35 being entirely a matter of adjustment, to determine whether one, two or more steps shall be taken before any of them can reach the contacts.

In Fig. 3 I have shown a detail of the 40 three soft iron frame pieces, with the magnet cores and windings removed, also with the release lever taken off, by loosening the screw, w' , which with the fixed pivot point, w^2 , support it in position. The vertical ratchet, z^{27} , of the spindle is engaged by a 45 pawl, l^2 , pivoted to the end of the armature, l^2 , of the vertical magnet, L . This armature is pivoted between ears, l' , formed on the frame, l , and normally rests against the adjustable back stop, l^6 , which is tapped into the 50 an extension on the frame. The toe of the pawl extends out through an opening, l^8 , cut into the plate, W' , just above the top of the knife edge, w^6 . The heel of the pawl is 55 pulled back toward the pivot point of the armature lever by means of a spring, l^4 . In order to assist gravity in pulling down the armature lever, l^2 and retracting the pawl when the magnet L is deenergized, I 60 provide a coiled spring on a spindle having an end key, l^7 , the spindle and spring extending parallel with the pivot of the armature, and the key resting in either one of the two diametral slots in the ears of the frame, 65 and serving when twisted to wind up the

spring so as to adjust it to any desired strength. The opening, l^8 , not only guides but limits the movement of the pawl, l^2 , which normally rests against its lower edge and is thereby turned upon its pivot so as 70 to be withdrawn from engagement with the ratchet, z^{27} , when the armature, l^2 , drops back. When the armature is attracted, on the other hand, the pawl is lifted off the edge of the opening, and the spring, l^4 , pulls 75 back its heel, throwing its toe forward through the opening, so that it will engage with and move the ratchet one step. It cannot go farther than this one step, by reason of the toe striking against the upper edge 80 of the opening, l^8 , which thus becomes the vertical limiting stop.

The frame, k , is three-sided, and carries between its left-hand ends the armature, k^3 , pivoted at its lower edge (looking down on Fig. 3) between the members, k' , k^2 . Secured to the lower part of the armature, near the pivot point, is a right-hand lever arm, k^3 , which normally lies away from the observer looking at Fig. 3, withdrawing the pawl, k^5 , 90 through the opening, k^6 , shown in Figs. 3 and 4. When the magnet K is energized, the armature, k^3 , is rocked on its pivots to the right in Fig. 3, as indicated by the arrow; the lever, k^3 , then comes forward toward the observer, (or to the right in Fig. 4) and pushes the toe of the pawl, k^5 , against a tooth of the rotary ratchet, z^{28} , so as to turn the same. The armature, k^3 , normally rests against an adjustable set-screw, k^8 , tapped into the extension, k^4 , on the arm, k' ; and the armature is held in this position by means of the coiled retracting spring, k^7 , secured at its lower end to the member, k^2 , and at its upper end to a key, k^{10} , similar to that shown at l^7 for magnet, L . It will thus be perceived that the walls of the opening, k^6 , serve as limiting stops for the rotary pawl, k^5 , just the same as those of the opening, l^8 , serve as limiting stops for the pawl, l^2 . The iron member, W' , in which these openings are formed, is punched and formed up so that it is always the same and interchangeable; moreover, its relation with the other members, l and k , is the same in all switches, by reason of the method of attaching these parts to the frame. They all fit into the rectangular space, and register with each other, being secured to the frame by suitable screws or other fastening devices passing through the frame. It will be observed, after studying Figs. 1, 2, 3, 4 and 6, that the magnets, K , L and W each with its iron frame and the parts attached thereto, can be separately removed from the frame, z^{21} . The magnets and their working parts are made up and assembled separately, and applied to the frame as units, which tends to economy and uniformity in manufacture. Whereas each of the magnets, K and L , has 130

two spools, the release magnet W has only one spool, its work being slight, and the parts which it moves being very light. When the magnet K is energized one or 5 more times it steps around the spindle, z, in a rotary direction, and the return of the spindle is prevented by the detent pawl, w⁵, on the pivot lever, w. When the magnet L is energized one or more times it lifts the 10 spindle vertically, and the same is prevented from falling by the pawl, w⁴, which engages the vertical ratchet, z²⁷. As soon as the vertical pawl comes into play the rotary pawl loses its function, since the ratchet wheel, z²⁸, then 15 engages the knife edge, w⁶, and cannot turn as long as the spindle remains raised. This condition persists until the detent lever, w, is rocked on its pivot by the magnet W, which occurs when the proper circuits are 20 closed as I have already pointed out in my description of the diagram. This lever, w, has a projecting arm, w³, which is shown on the side toward the observer in Fig. 1 and on the side away from the observer in Fig. 25 7. The lever being pivoted on the soft iron frame, W', and the pivot screw and point, w¹, w², being preferably of iron, the magnetic circuit is completed through the frame member, W', the core of magnet W through 30 the arm, w³, and the body of the lever, w. When the magnet is energized the arm, w³, is drawn in to its pole, and in order to facilitate this operation I prefer to curve the end of the arm somewhat, to form a hook partly 35 surrounding the pole of the magnet. When the arm is attracted to the pole, the lever, w, is rocked on the pivots, w⁰, w², and the toes of the two detents, w⁴, w⁵, are removed from engagement with the ratchets, z²⁷, z²⁸, the 40 latter being then released so that spring pressure or gravity or both may return the spindle to its initial position as shown in the figures. The return of the spindle, z, in a rotary direction to its initial position is ac- 45 complished by means of a coiled spring surrounding the spindle, at z²¹, one end of this spring being tapped to the spindle and the other to the lever, z²², whose end is fitted to and travels in a longitudinal slot cut in the 50 inner face of the frame, z²¹. The initial position of the spindle is determined and fixed by means of the stop lever, z²⁴. This lever is carried rigidly on the spindle in a yoke, z²⁵, which may be adjusted and then locked 55 upon the spindle.

The contact strip, Z', is made and assembled separately from the switch, and is adapted to be secured to the unit section cabinet so that when the switch is placed 60 therein it will register with the strip and may be secured thereto. The strip consists essentially of two channeled side bars, z²⁶, z²⁷, secured together by screws, z²⁸, and clamping between them one hundred sets of 65 contact springs, each set associated with a

line or trunk circuit. These one hundred sets are divided into ten groups, which I have indicated in Fig. 1 by the letters z⁰, z¹⁰, z²⁰, z³⁰, z⁴⁰, z⁵⁰, z⁶⁰, z⁷⁰, z⁸⁰, z⁹⁰. Below each group I leave a space, z³⁹, z⁴¹, z⁴², z⁴³, z⁴⁴, z⁴⁵, 70 z⁴⁶, z⁴⁷, z⁴⁸ and z⁴⁹. Opposite these spaces, I secure upon the spindle radial studs, z¹, z⁸, z⁹, z¹¹, z¹², z¹³, z¹⁴, z¹⁵, z¹⁶, and z⁵¹. These studs are set helically around the spindle, as clearly indicated in Fig. 5, to which I will 75 now refer in order to make clear the construction of the contact strip. Each set of springs comprises a pair of outside line springs, z⁵, z⁶, a pair of trunk springs, z', z² and a pair of test springs, z³, z⁴. Interposed between these springs are strips of insulation, preferably of hard rubber, and the whole is joined together by the side bars, z³⁶, z³⁷, through the medium of the screws, z³⁸, which it will be observed are inserted in 80 the spaces between the groups of springs. All the springs, z³, through the length of the entire strip are connected together, and may in fact be merely projecting comb teeth on a common plate or strip. All of the springs, 85 z⁵, z⁶, are individual springs, that is each pair forms outgoing line or trunk terminals. All of the springs, z', and all of the springs z², are joined together throughout the entire strip, and therefore these also may merely 90 be teeth on a comb. The springs, z⁴, however, are individual, each being associated with a pair of springs, z⁵, z⁶, so that when the spring, z⁴, is tested it indicates the condition of the circuit connected to the other 95 two named. One of the studs being brought in line with one of the groups of contacts by means of rotary movement of the spindle, z, is then moved up vertically by the corresponding movement of the spindle, passing 100 between one pair after another of the contacts z³—z⁴, and bridging across each pair as it passes. I might dispense with the common contact set, and make the studs carry the test current as wipers, but I prefer 105 to have all the contacts fixed and no circuit carried through the spindle or other moving parts. As the stud passes upward between these test contacts, it also spreads apart the contacts z'—z², which move with the inner 110 contacts by reason of the interposed extended strips of insulation shown in Fig. 5. These then make contact with the outer springs z⁵—z⁶, so that at the instant the pair of springs z³—z⁴ is bridged to complete the 115 test circuit, the outer springs z⁵—z⁶ and z'—z² are connected to complete the line or trunk circuit correspondingly.

The frame z²¹ has the ends of its transverse members z²³ received into mortises 120 formed in solid end pieces fitted between the side bars z³³—z³⁷ of the contact strips, and is secured in this position by screws z⁵³—z⁵² passing through lugs z⁵³—z⁵⁴ formed on the inner faces of the end mem- 130

bers z^{22} , z^{23} , and tapped into said solid end pieces, which are indicated in Figs. 1 and 10 by the letter z^{53} . The end members themselves, z^{23} , are partly cut away at z^{56} to form shoulders which rest against the inner faces of the contact strips and the solid end pieces thereof, so as to afford a positive and invariable means of alinement for the switch parts with respect to the contact strip.

Referring now to Figs. 8 to 14 inclusive, I will describe my unit section cabinet. In Fig. 8 this is shown with five switches Z slid into place, looking at them from the front. None of the contact strips are shown which belong to these switches. The frame P of the unit section is formed of four vertical channel irons, two at each end, set parallel to each other, transversely connected across the top and bottom at each end by an angle iron p^1 , and longitudinally connected front and back by the upper and lower angle irons p^2 . A skeleton frame or cage is thus formed, which I close on the top, bottom and ends by means of sheet iron. On the ends this is shown as a plain facing p^3 , held in place by being passed between the angle and channel iron before they are secured together, which I preferably do by riveting. The top and bottom closures, however, have another function, which is to support and serve as guides for the switches Z . As shown in Figs. 8 and 11, these are lettered p^4 . Each is provided with a series of transverse grooves p^5 formed in it by rolls or dies. A convenient method of forming this material with the grooves in it is to pass strips of the required width between two rollers or cylinders, one of which has transverse grooves and the other has corresponding transverse projections to register with the grooves as the rolls are rotated. These strips may then be cut into the desired length, and secured in place as shown in the figures by bolting or riveting the ends, preferably the latter.

The contact strips Z' are secured vertically upon the upper and lower longitudinal angle irons on the back of the frame, as shown in Fig. 10, and as indicated in plan in Fig. 11. The simplest way of securing these in place is by the screws z^{59} passing through the upper and lower end pieces z^{53} , and tapped into the faces of the angle irons. These strips being thus fixed upon the frame, support upon their rear faces all the circuit wires leading to their contacts, that is, all the wiring of the switches, except only the wires leading to the three magnets K , L and W , which are suitably disposed upon the frame of each switch, z^{21} and terminate in contacts z^{57} coöperating with fixed contacts z^{58} (see Figs. 1 and 10). The strips being all in position, the operating portions of each switch are introduced from

the front by sliding them into the grooves p^5 in the top and bottom plates p^4 . As they are slid into place they automatically aline themselves with the contact strips, by the ends of the end flanges z^{26} entering the mortises in the blocks z^{55} of the strips, and the shoulders z^{56} coming against the inner faces of the strips. Screws z^{51} and z^{52} are then turned home in the lugs z^{53} and z^{54} , so as to hold the parts in position. It will be apparent from this description that the magnets K , L and W are brought into connection with their respective circuit wires by the mere act of inserting the switch parts in the frame; and the entire switch body is therefore instantly detached, and all the switch bodies are absolutely interchangeable. In manufacturing and assembling they are all set up and tested in a common frame and with a common set of contacts, in addition to which the other contact strips are all made in the same templet, which itself is made from the common set of contacts with which the switch bodies are tested, hence there can be no variation, but all parts are standard.

Referring to Figs. 12, 13 and 14, I here show the method of assembling my unit sections into a complete cabinet. In Figs. 12 and 13 I give a front and a side elevation, respectively, of a cabinet formed by aggregating four unit sections, two bases and two tops. Each of the unit sections is shown at P . Each of the tops is shown at N , and each of the bases at N' . It will be observed from Fig. 13 that the top N and base N' are both of greater depth than the skeleton frame $p-p$, $p'-p'$. This is in order to allow a certain space on the back of the frames for the strips Z' and their cover plate, which I preferably make of sheet iron and secure in place as shown in Figs. 9, 11 and 13. The top and bottom members p^1 are extended back of the frame, and along their rear edges fitted with a stiffening angle plate p^6 . The sheet iron end cover p^3 is also extended back to the rear edge of the angle iron p^6 , and across the whole rear face of the section, from one angle plate p^6 to the other is extended a straight piece of sheet iron p^7 , secured by detachable devices such as screws p^8 . It will be perceived that in the rear of each frame there is an inclosed chamber which I have marked p^9 in Fig. 11, open at the top and bottom, and permitting the passage of circuit conductors to the strips. The top N and the base N' are made of sufficient depth to cover the top and bottom, respectively, of these chambers, and since the base is hollow, being itself formed of sheet metal with a stiffening frame, the cables may be led down from the strips and through the base to any desired point. The back of the base for this purpose is also fitted with a removable cover p^{10} . In order to carry the

- weight which is placed upon it, each base section N' is formed with a skeleton frame having vertical members n' , two at each end, registering with and of the same shape as the channel irons p of the unit sections. These end members are united top and bottom by longitudinal members n^2 , which may advantageously be angles, and transversely they are united at their front ends by their angle bases n^3-n^4 , the latter of which is extended out front and rear to give a wide footing for the base. Upon this skeleton frame is fitted the sheet iron cover n , having an ornamental front, and end pieces, with a removable back. This cover as well as all of the other parts of the cabinet may be painted or enameled, or galvanized or otherwise treated to preserve and ornament the metal.
- 20 The top N is made in any suitable or preferred manner from sheet metal, with accurately fitted edges so that it will take over the top of the upper unit section P all around, and close the same in a substantially dust and moisture-proof manner.
- 25 Each section P of the cabinet is closed in front by a metal cover p^{11} , fitted, if desired, with a glass panel p^{12} . I have shown only one of these covers, and it should be understood that they may be merely of iron without panels, if desired. Glass used in such relations is very liable to breakage, and the panels are large enough to be quite expensive, hence I prefer plain iron covers, except where it is desired to have the cabinet present an ornamental appearance. I have shown covers secured at top and bottom by screws p^{13} , upon loosening which the same may be removed by means of the handle p^{14} .
- 30 40 The edges of this cover may rest all around upon a strip of felt, to exclude dust and moisture, and the same material may, in fact, be used elsewhere in the joints, if desired, for the same purpose.
- 45 It remains to describe the method of fastening the unit sections together to form the cabinet. For this purpose I employ corner blocks N^2-N^3 , shown in Fig. 14. These are of proper shape to have their bodies slid into the channel in the end members p of the frames. As clearly shown in Fig. 12, there are four of these members for each unit section P , and four for each base N' . The top N has none, but is fitted with end sockets to receive those of the section P upon which it may be placed. In building up a cabinet, the base is first set down upon the floor, and fastened if desired by screwing down the end strips n^4 . This base has four corner blocks sticking up, and the section P which comes next in order is placed upon the base so that these blocks will enter the channels of its end members p . At the top of this section there are four other blocks sticking up, and if another section is
- added, it is similarly placed upon the first one, so that these blocks will enter its end members, and so on, until the case is finally placed upon the top section P , with the blocks thereof entering its sockets and holding it in place. Where two vertical sets are to be piled up, as shown in Fig. 12, the two bases N' are first laid down and secured, and then the blocks N^2-N^3 of the bases which come together receive a bolt shown in dotted lines in Fig. 12, at n^5 . These two bolts confine the bases together, and when the sections P are put upon them, they confine these sections together also at the bottom. The blocks N^2-N^3 on the two sections at their meeting places are then bolted together in the same manner, and so on up, each protruding pair of blocks being bolted together before the next pair of sections P is put in place; so that when the two tops N are finally superposed on the cabinet, the whole is firmly tied together and cannot be disturbed except by vertically lifting the members apart, which their own weight and the weight of their contents sufficiently provides against. In order to insure great steadiness, the blocks N^2-N^3 may be made as long as desired, extending up and down in the channel irons, so that all of the channel irons in vertical line with each other are virtually united to form a single vertical member supporting racks for the switches.
- 50 The designs herein shown are intended for a case where the switches in one unit section are those which contain multiples of the same trunk or line circuit. Instead of putting these side by side I may put them vertically above each other for convenience in wiring the multiples; and I may make the frames of other material than iron; but such changes, and many details which will at once occur to those skilled in the art after reading this specification, I do not describe herein, and do not specifically claim, wishing it understood nevertheless that they are included within the scope of my invention, and while generically covered herein, may be specifically covered in other cases.
- Having thus described my invention what I claim and desire to secure by Letters Patent is:
1. A switch for automatic telephone systems, comprising a flat open frame having projecting ends, a straight strip of contacts extending parallel to the body of said frame between the ends thereof, an operating member mounted in the frame longitudinally thereof and parallel with the strip of contacts, and electro-magnetic means for actuating the operating member mounted upon the frame, substantially as described.
2. A switch for automatic telephone systems comprising a flat frame having projecting ends, a strip of contacts secured between the ends parallel to the body of the

- frame, an operating member for said contacts extending parallel thereto and carried upon the frame, and electro-magnets for actuating said member also mounted within and upon the frame, substantially as described. 3. A switch for automatic telephone systems comprising a flat open frame, stiffening flanges upon said frame, a contact strip connected to said frame, an operating member for the contact strip carried in the frame, and electro-magnetic actuating means for said member supported in and upon the frame, substantially as described. 4. A switch for automatic telephone systems comprising a flat open frame, a straight strip of contacts mounted lengthwise of the frame, an operating member mounted in the frame parallel thereto, and electro-magnetic actuating means for the operating member also mounted in and upon the frame, the dimensions and arrangement of all the parts being such as to constitute a structure having relatively greater length than thickness, substantially as described. 5. A switch for automatic telephone systems comprising a flat frame of considerable length relative to its thickness, with stiffening flanges and projecting ends, a straight strip of contacts and an operating member therefor secured to the frame within the ends, and electro-magnetic actuating means for the operating member carried upon and within an intermediate portion of the frame, all the parts being so proportioned and arranged as to lie substantially within the thickness of the frame, substantially as described. 6. A switch for automatic telephone systems having a frame composed of longitudinal body members and transverse projecting end members, with stiffening flanges all lying between the same planes, and of small thickness relatively to the end of the frame together with contacts, an operating member therefor, and electro-magnetic actuating means all secured upon and lying substantially within the thickness of the frame, substantially as described. 7. A switch for automatic telephone systems comprising a long flat frame, with operating parts all mounted upon and within the thickness of the frame, and contacts constituting line terminals arranged in a straight line and in general parallelism with the major dimension of the frame, substantially as described. 8. A switch for automatic telephone systems comprising a flat and open frame with extended longitudinal members and transverse ends, a strip of contacts mounted to lie parallel with the longitudinal members and between the ends, an operating spindle coöperating with said contacts and mounted upon the frame between the ends thereof, and actuating means for said spindle also mounted on the frame, substantially as described. 9. A switch for automatic telephone systems comprising a flat frame having extended longitudinal members and transverse ends, contacts secured to said frame, and a tubular operating spindle working upon studs secured to the ends thereof, substantially as described. 10. A switch for automatic telephone systems comprising a frame, movable contact members, fixed terminal contacts in longitudinal order, and a tubular operating spindle working upon studs in the frame, substantially as described. 11. A switch for automatic telephone systems comprising an elongated frame carrying an operating member extended in the direction of its length, and electromagnetic actuating means therefor intermediate of its ends, a straight supporting strip detachably secured at its ends to the ends of the frame, and a plurality of contacts for the operating member supported in said strip, substantially as described. 12. A switch for automatic telephone systems comprising an elongated frame, operating parts mounted thereon to work on the long axis thereof, a straight line unitary mounting strip in substantial parallelism with the said long axis of the frame, a plurality of contacts secured upon said strip, and detachable connections between the frame and the contact strip, substantially as described. 13. A switch for automatic telephone systems comprising an elongated flat frame having an open central portion, and operating parts mounted thereon in the opening approximately within the thickness of the frame, substantially as described. 14. A switch for automatic telephone systems comprising an elongated frame, contacts in straight line parallel relation thereto, terminal studs secured upon said frame, and a tubular spindle lying parallel with and coöperating with the contacts and working upon said studs, substantially as described. 15. A switch for automatic telephone systems comprising a flat elongated frame having a wide central portion and reduced ends, a spindle extending in the direction of its length, and the central portion open, with electro-magnetic actuating means for the working parts mounted upon the frame within said central portion, substantially as described. 16. A switch for automatic telephone systems comprising an elongated frame, electro-magnetic actuating means mounted thereon, contacts therefor supported in a straight line, in a fixed strip, and means for detachably securing the ends of the frame 125 130

to the contact strip with the actuating parts in operative relation with said contacts, substantially as described.

17. A switch for automatic telephone systems comprising a support, a straight bank of contacts rigidly mounted as a unit on said support, and an elongated switch frame carrying operating parts extending along an axis parallel to said bank, and adapted to be detachably secured upon said contact bank, substantially as described.

18. A switch structure for automatic telephone systems comprising a support, a straight bank or strip of contacts rigidly mounted as a unit upon said support, a frame carrying parts extended along the length of the frame, adapted to coöperate with said contacts, and means for detachably securing said frame upon said bank with the coöperating parts in working parallel relation with the contacts, substantially as described.

19. A switch structure for automatic telephone systems comprising a support, a straight bank or strip of contacts rigidly carried upon said support, a switch frame carrying working parts extending in parallelism to said bank, guiding means on the support over which the switch frame is adapted to travel and means to secure the switch frame upon and in operative relation to said guiding means and thereby to adjust it on the support with its parts in operative relation to the contacts, substantially as described.

20. In an automatic telephone system, a switch system comprising a support, separable units carried on the support, each unit having a plurality of sets of contacts carried upon it, and a switch frame carrying operating parts, adapted to be detachably connected with and carried on each unit in operative relation with its contacts, substantially as described.

21. Automatic switching apparatus for telephone systems comprising a support or frame structure in separable interchangeable units each complete in itself, a plurality of individual switch banks mounted in parallelism upon each unit, and a plurality of associated interchangeable switch frames carrying working parts detachably secured in operative relation to the respective banks, substantially as described.

22. Automatic switching apparatus for telephone systems comprising separable groups of fixed banks and detachable individual switches, each group mounted and secured together as a unit and all groups or units being interchangeable, substantially as described.

23. Automatic switching apparatus for telephone systems comprising a supporting structure formed of an aggregation of separable units, each unit composed of an in-

closure complete in itself, and a complete group of switches containing related multiples, mounted in each supporting unit, substantially as described.

24. Automatic switching apparatus for telephone systems comprising a supporting structure formed of an aggregation of separable units, each unit complete in itself and all units interchangeable, together with a plurality of switches containing related multiples mounted detachably in each unit, substantially as described.

25. Automatic switching apparatus for telephone systems composed of a built-up aggregation of separable and interchangeable units, each composed of a complete and symmetrical group of fixed banks and detachable interchangeable switches, and a containing case, substantially as described.

26. In automatic switching apparatus for telephone exchanges, a supporting structure comprising a plurality of unit cabinets having metal frames and mounting strips, said units being interlocking and separable without the use of tools, a set of contact banks or strips carried on the mounting strips in each unit, and a corresponding set of frames with operating parts detachably connected to said banks and inclosed within the unit cabinets, substantially as described.

27. Switching apparatus for telephone exchanges comprising an aggregation of separable unit cabinets having means to pass cable from each unit to and through other units without interference, and with a complete unit group of switches containing multiples of the same group of circuits, mounted and inclosed within each unit cabinet, substantially as described.

28. In a telephone exchange system, switching apparatus composed of a plurality of separable and interchangeable self-contained units, each unit comprising a complete and symmetrical group of fixed banks and detachable switches assembled and connected together for switching a definite number of circuits, substantially as described.

29. In a telephone exchange system, an automatic switch outfit comprising a frame, inclosing walls for said frame, mounting strips secured upon said frame, switch banks secured in a homogeneous group upon said mounting strips, and frames carrying the working parts of the switches secured upon said banks, and a front plate or panel for inclosing the frame and contacts, substantially as described.

30. Telephone exchange switching apparatus built up of standard interchangeable units each comprising a frame formed of metal strips or angle bars with sheet metal inclosing walls, and a group of automatic switches mounted within and upon said frame, substantially as described.

31. In a telephone exchange system, a switching structure comprising a plurality of separable and interchangeable units each composed of a group of inclosed and protected switches, and a fixed contact bank for each switch, having terminals with the outer ends exposed and the inner ends inclosed and located in operative relation to the switch contacts, substantially as described.

32. Automatic switching apparatus for telephone systems composed of a built-up aggregation of separable and interchangeable units, each composed of a complete and symmetrical group of relatively fixed banks with separable and interchangeable switches, substantially as described.

33. Automatic switching apparatus for telephone systems composed of a built-up aggregation of relatively fixed but separable and interchangeable groups of separable and interchangeable switches, each group complete for a predetermined number of lines, and each switch composed of separable and interchangeable parts, substantially as described.

34. A step by step selector switch comprising bank contacts, a spindle and wipers carried thereon, together with actuating mechanism for the spindle adapted to rotate the same and also to reciprocate it in a vertical direction, a rotary ratchet carried on the spindle, and a knife edge carried on a fixed portion of the switch body normally out of contact with said ratchet but adapted to engage the same when the spindle is reciprocated and thereby prevent rotation of the spindle except in one position.

35. A step by step selector switch having contacts, wipers, a rotary ratchet, fixed and movable means for actuating and holding said ratchet, said fixed means being normally disengaged from the ratchet, and means for causing engagement of the ratchet by said fixed holding means.

In testimony whereof I affix my signature in presence of two witnesses.

EDWARD E. CLEMENT.
